(57) **CLAIM**

The ornamental design for a lighting fixture, as shown and described.

DESCRIPTION

FIG. 1 is a first perspective view of a lighting fixture showing my new design;

FIG. 2 is a front elevational view thereof;

FIG. 3 is a rear elevational view thereof;

FIG. 4 is a left side elevational view thereof;

FIG. 5 is a top plan view thereof;

FIG. 6 is a bottom plan view thereof; and,

FIG. 7 is a second perspective view thereof.

This invention relates to a lighting fixture. The right side elevational view thereof is a minor image of the left side elevational view thereof. The broken lines showing elements of the lighting fixture in FIGS. 1-7 are shown for illustrative purposes only and form no part of the claimed design.
